(57) **CLAIM**

The ornamental design for a cine cap, as shown and described.

DESCRIPTION

FIG. 1 is a top, perspective view of a cine cap, in accordance with the present design, illustrating the cine cap connected to a camera lens;

FIG. 2 is a top, plan view of the cine cap; and,
FIG. 3 is a side, elevational view of the cine cap, wherein all side elevational views of the cine cap are the same.

The broken lines of FIG. 1 define the environment on which the cine cap may be secured, and form no part of the claimed design.
